UNITED STATES PATENT OFFICE.

DANIEL A. LOESER, OF SAG HARBOR, NEW YORK.

DESIGN FOR A SPOON OR FORK HANDLE.

SPECIFICATION forming part of Design No. 25,020, dated December 31, 1895

Application filed November 30, 1895. Serial No. 570,703. Term of patent 7 years.

To all whom it may concern:

Be it known that I, DANIEL A. LOESER, a subject of the Emperor of Germany, residing at Sag Harbor, in the county of Suffolk and 5 State of New York, have invented and produced a new and original Design for Spoon or Fork Handles, of which the following is a specification, reference being had to the accompanying drawings, in which—
10 Figure 1 is a view of the obverse side of a spoon the handle of which has my new design applied thereto, the tines of a fork being shown in dotted lines. Fig. 2 is a view of the reverse side thereof, showing my design applied to the 15 handle.

The leading or characteristic feature of my design consists of a series of scrolls, increasing in size toward the outer end of the handle and decreasing in size in the opposite direction, where they terminate in a foliated border.

Referring to the drawings, A represents the handle of a spoon or fork the obverse side of which, as shown in Fig. 1, has applied thereto 20 my design, consisting of a series of scrolls B, decreasing in size toward the bowl of the spoon 25

and terminating in the foliated border C, the surface D, lying between the scrolls, being left plain.

On the reverse side of the handle, Fig. 2, is a series of leaves E, decreasing in size from 30 the outer end of the handle toward the bowl of the spoon, which leaves radiate from the center of the handle toward the outer edge thereof and join with the foliated border F, similar in design to the border C on the ob- 35 verse side.

What I claim is—

1. The design for the handle of a spoon or fork as set forth.
2. In the design for the handle of a spoon 40 or fork, the design of the obverse side of the handle, as set forth.
3. In the design for the handle of a spoon or fork, the design of the reverse side of the handle, as set forth.

DANIEL A. LOESER.
